REPRODUCTION MACHINE OF THE
PANTOGRAPH TYPEGeorge M. Keczeli, Colorado Springs, Colo., as-
signor to Mary M. Keczeli, Colorado Springs,
Colo.

Application December 30, 1948, Serial No. 68,329

20 Claims. (Cl. 90—13.1)

1

My invention relates to a reproduction machine of the pantograph type. It has to do, more particularly, with a pantographic reproduction machine designed for reproducing from a master, such as a template pattern, drawing, or an actual article to be duplicated, an article of the same or different size, by various forming operations. Depending upon the type of article to be made and the material thereof, my machine may form the article by milling, cutting, planing, routing, drilling, grinding, hammering, engraving, or by various other operations. Regardless of the type of tool used in the formation of the article, my machine will effectively control and guide it to reproduce the article from the master in the same ratio or in a reduced or increased ratio.

Various pantographic reproducing machines have been developed and used in the past. However, these machines have usually been designed for delicate reproduction of small articles and are not suitable for heavy reproduction work. The prior art machines have not been sufficiently rigid and sturdy to perform such heavy work as milling, planing, etc. These machines have usually included small work-supporting tables and have been limited in use to the producing of small articles which could be accommodated by the tables. These prior art machines have usually included complicated driving mechanism for the forming tool which mechanism is generally so located as to interfere with free manipulation of the machine in the reproduction operation. Also, the drive has usually been of such a nature as to interfere with the necessary adjustments to change the ratios of the reproductions. Furthermore, the forming units of the prior art machines have not been mounted and counterweighted properly to facilitate movement thereof even though the unit might be of a heavy sturdy type. With prior art machines, the necessary adjustments of the tracer unit and the forming tool unit relative to the master and work, respectively, have been difficult to make and it has been difficult to properly control and limit the feed of the tool into the work. With prior art machines, the table is usually adjusted relative to the pantograph and this type of structure detracts from the rigidity of the machine. Prior art machines usually have not been so constructed as to make it possible to interchange tools for various forming operations.

One of the objects of my invention is to provide a pantographic reproduction machine of simple structure and operation, and one which is very

2

efficient, even when operated by an unskilled person, for accurate reproduction work by accurate control of a forming tool of any of various types.

5 Another object of my invention is to provide a pantographic reproduction machine which is designed and constructed to be extremely rigid and sturdy so that it will be especially suitable for heavy duty work, such as heavy milling, planing, etc., and will still be accurate in controlling such work.

An additional object of my invention is to provide a pantographic reproduction machine which though designed to handle heavy duty work can also handle light delicate work, such as, engraving, drawing, etc., and which consequently, is a versatile machine which can be used in almost any work where a master is provided for reproduction.

A further object of my invention is to provide 20 a pantographic reproduction machine which is provided with a large supporting table for receiving the work but which is so arranged that the forming tool unit can be moved to a position alongside the table to work on large heavy pieces 25 of material disposed alongside the table.

An additional object of my invention is to provide a machine of the type indicated in the preceding paragraph wherein the table is rigidly supported in a stationary position and the forming unit and guiding unit are adjustable relative to the table and are movable relative to the table, which provides for an extremely rigid work-supporting structure.

Still another object of my invention is to provide 35 a pantographic reproduction machine of the type indicated above which is of rugged structure for heavy duty work but in which the forming unit is so arranged and counterweighted as to facilitate the necessary controlled and guided movement thereof in the forming operation.

Another object of my invention is to provide a machine of the type indicated wherein the drive for the forming unit is so arranged as not to interfere with any necessary adjustments of the 45 machine or with the operation of the machine.

A further object of my invention is to provide 50 a pantographic reproduction machine including a forming tool unit, the movement of which is controlled by a tracer unit and wherein the adjustment of the tool to the work and the tracer to the master can be made with ease and the feed of the tool into the work can be controlled and limited in a proper manner.

An additional object of my invention is to provide 55 a pantographic reproduction machine which

is so designed that the forming unit may accommodate forming tools of various standard types which can be interchanged with ease.

Various other objects will be apparent from the drawings and the following description.

According to my invention, I provide a pantographic reproduction machine which comprises a large sturdy and rigid supporting table. Upon this large table I provide means for supporting the master to be reproduced and means for supporting the workpiece upon which the forming operation is to take place. The workpiece is attached to a plate which may be fastened firmly to the table at various locations, suitable guides being provided for aiding in locating it on the table. The master or template is adapted to be firmly secured to a supporting plate or table which, in turn, is attached to the main table. Suitable guides are provided on the master table for locating the master thereon in various positions. In addition, means is provided for adjustably securing the master table to the main table at either of two diagonally opposite positions adjacent the ends of the table. These positions are such that in one position of the master table, the work produced on the workplate will be a direct image of the master on the master table, and in the other position of the master table, the work produced on the workplate will be an image of the master on the master table but will be swung around 180° relative to the master in the plane of the master or a plane parallel thereto.

At one side of the table intermediate its ends, an upstanding supporting column is provided and its base is rigidly attached to the table. This column carries a supporting sleeve and mechanism is provided for adjusting the sleeve vertically on the column and for then rigidly clamping it to the column in adjusted position. The sleeve supports a jointed arm which extends over the table and is pivoted to the sleeve for horizontal swinging movement. The outer end of this arm carries a forming tool unit and a driving motor which are arranged to counterbalance each other. Connected to the sleeve on the column is a second pivoted arm which extends outwardly over the table below the first arm end which is also adapted to swing horizontally. The outer end of this arm is connected to a pantograph frame which is disposed horizontally and parallel to the table. The pantograph is also connected to the forming tool unit so as to control movement thereof relative to the column. The connections between the pantograph and the forming tool unit and between the pantograph and its supporting arm are adjustable so as to change the ratio of reproduction. The pantograph is also provided with a detachable arm which supports for vertical adjustment a tracer adapted to be associated with the master. This arm is adapted to be disposed at diagonally opposite points on the pantograph, corresponding to either of the diagonally opposite locations of the master table on the main table. The forming tool unit is so designed as to permit interchange of various tools and includes means for gradually feeding the tool into the work and means for limiting the feed into the work.

The preferred embodiment of my invention is illustrated in the accompanying drawings wherein similar characters of reference designate corresponding parts and wherein:

Figure 1 is a perspective view, partly broken away, of my pantographic reproducing machine.

Figure 2 is a plan view of my machine.

Figure 3 is a vertical sectional view taken along

line 3—3 of Figure 2 through the supporting standard for the forming unit and pantograph unit of the machine.

Figure 4 is a side elevational view of part of the structure shown in Figure 3.

Figure 5 is a horizontal sectional view taken along line 5—5 of Figure 3.

Figure 6 is a vertical sectional view taken substantially along line 6—6 of Figure 2 through the tool holding unit of my machine.

Figure 7 is a side elevational view of the structure of Figure 6.

Figure 8 is a vertical sectional view taken along line 8—8 of Figure 2 through the tracing pin unit or master follower unit of my machine.

Figure 9 is a vertical sectional view taken along line 9—9 of Figure 2 showing the pantograph arm, which carries the tracing pin, connected to the pantograph at the side of the table where it is disposed when the reproduction is to be a direct image of the master.

Figure 10 is a vertical sectional view taken along line 10—10 of Figure 2 showing the pantograph arm, which carries the tracing pin, connected to the pantograph at the corner diagonally opposite to where it is connected in Figure 9.

Figure 11 is a vertical sectional view taken along line 11—11 of Figure 2 through the master supporting table carried by the main supporting table.

Figure 12 is a vertical sectional view taken through the master supporting table at right angles to the section of Figure 11.

With reference to the drawings in Figures 1 and 2 I have illustrated my machine generally. It comprises a large elongated table 1 which is of rigid and sturdy construction, preferably being formed of metal. The table comprises the top 2, which is in the form of a thick plate carried by a suitable number of legs 3 rigidly fastened thereto. For locating the workpiece on the top surface of the plate 2, a straight edge 4 is provided and may be bolted in any of a number of positions by means of the bolts 5 which are passed through pairs of openings 6 provided in such plate. Guide lines 7 correspond with the pairs of openings 6 and aid in locating the straight edge 4. The workpiece W is carried on a platen 8 which will be disposed against the straight edge 4. The platen 8 is adapted to be clamped to the table top by suitable clamping means, such as by screws 9 which can be passed into openings or slots (not shown) formed in the table top 2.

The table top 2 is adapted to carry a master supporting table 10. This table 10 is preferably in the form of a thick sheet or plate of transparent plastic. The table 10 is adjustably supported on the table top 2 at one end thereof by means of a guide track or guide bar 11. This bar 11 is secured to guide brackets 12 at its ends, which depend therefrom and each of which is provided with a guideway 13 which slides on the adjacent edge of the table top 2. Thus, the member 11 may be moved laterally of the table but can be fixed in a definite position by means of the rod 14 which is anchored to one of the brackets 12 and which is provided with a clamping nut 15 threaded on its opposite end, it being understood that this end of the rod loosely passes through the adjacent bracket 12. This structure is shown more in detail in Figure 12. It will be apparent that by operating the clamping nut 15, the brackets 12 may be clamped to the front

75 and rear edges of the table top 2.

The table 10 is mounted on the member 11 for movement forwardly and rearwardly of the table top 2. For this purpose, the lower surface of the table 10 is provided with a guideway 16 adjacent one end thereof and extending from its front edge to its rear edge, as shown best in Figures 1 and 11. The table 10 carries a clamping bar 17 on its lower surface by means of a pair of depending screws 18. This bar will be disposed below the bar 11 and transversely thereof and by tightening screws 18, the table 10 can be clamped to the bar 11. The table 10 may have several pairs of openings 19 for receiving the screws 18. Thus, it will be apparent that the table 10 can be adjusted both forwardly and rearwardly of the table top 2 and also laterally of the table top. When desired, the guide bar 11 may be slipped from the one end of the table top 2 and be slipped on other end of the table top 2, for a purpose to be explained later, so that table 10 will be in a diagonally opposite position at the rear of the main table, as shown by the dotted lines in Figure 2.

The master supporting table 10 is provided with a series of pairs of openings 23 for receiving pairs of bolts 21 that are used to attach a straight edge 22 thereto in various positions. The straight edge 22 is adapted to aid in locating a master supporting platen 23. This platen 23 will have the master M suitably secured thereto and may be secured to the plate 10 by any suitable clamping means, such as by the clamping screws 24 passing into any of the number of sets of openings 25 provided in the table 10.

Secured to the table top 2 at the rear edge thereof and intermediate the ends thereof, is a supporting column 26. This column is provided with a base 27 which is bolted by means of bolts 28 to the table top 2. The structure of this column is illustrated best in Figures 1, 3, 4, and 5. The column 26 is in the form of a tube which is inserted in the upstanding collar 29 on the base 27. A set screw 30 retains the tube within the collar. Slidably mounted on the exterior of the tube 26 is a sleeve 31 which is adapted to be moved vertically thereon. The sleeve 31 is split and is provided with a clamp 32 by means of which it may be clamped to the column 26. When the clamp is released, the sleeve can be moved vertically on the column by means of a screw 33. This screw 33 is rotatably carried in a cap 34 which is secured in the top of the column. This screw depends into the column and is provided with a threaded lower end which passes through a threaded collar 35. This collar 35 is provided with a radially extending portion 36 which extends through a vertical slot 37 formed in the column. The portion 36 is bolted by bolts 36a to the upper end of the sleeve 31. The screw 33 is rotated by means of a handle 39 keyed to the upper end thereof. It will be apparent that rotation of handle 39 will move the sleeve 31 up or down on the column, the movement being limited by the upper and lower ends of the slot 31. A lubricant fitting 38 is provided for supplying lubricant to the collar 35. The upper end of the screw 33 preferably has a calibrated dial 40 carried thereby for cooperating with an index point on the cap 34 to indicate the vertical position of the sleeve 31 on the column 26.

The sleeve 31 carried by column 26, supports for horizontal swinging movement a jointed supporting arm 41 which projects forwardly over table top 2. This arm includes a main section 42 pivoted by a vertical pivot pin 43 to the

forwardly projecting ears 44 on the upper and lower ends of the sleeve. The ends of the pin are rotatably carried in the ears 44 by means of anti-friction bearings 45 (Figure 3). The pin 43 passes through the ends of the upper and lower portions of the section 42 of the arm, being keyed therein as indicated at 46. Pivoted to the outer end of the section 42 of the arm by a vertical pivot pin 47 is a second arm section 48. The pivot pin 47 is arranged substantially the same as the pin 43 and has the anti-friction bearings 49 associated therewith. The outer end of the arm section 48 carries the vertically disposed sleeve 50 of the forming tool unit. Bolted to the side of the arm section 48 adjacent its inner pivoted end by means of bolts 51 (Figure 2) is an electric motor housing 52. The sleeve 50 (Figure 1) has a spindle 53 extending upwardly therefrom and upon which is keyed a multiple sheave 54. Similarly, the motor 52 is provided with an upstanding drive shaft 55 which has a multiple sheave 56 keyed thereon. The sheaves 54 and 56 include sections of different diameters and are reversed relative to each other. With this sheave arrangement any desired driving ratio may be obtained by changing the position of the driving belt 57 on such sheaves. The sheaves 54 and 56 are interchangeable to reverse the ratio of speeds.

As shown best in Figure 6, the spindle 53 is rotatably mounted in an anti-friction bearing 58 which is carried by a cap 59 mounted on the upper end of the sleeve 50. This spindle 53 extends downwardly into the sleeve 50 and its lower end is carried by a second anti-friction bearing 60 disposed within the sleeve 50 at a substantial distance below its upper end. It will be noted that the upper end of the spindle 53 is solid and is keyed by the key 61 to the sheave 54. However, the lower end of the spindle 53 is hollow, being provided with the socket 62 for receiving the upper end of a solid spindle 63. The spindle 63 is provided with nuts 64 threaded thereon below bearing 60, and which rest on an anti-friction bearing 65. The bearing 65 is disposed within the upper end of a second and smaller tube 66 which is mounted for telescoping movement within the lower portion of the sleeve 50. Within the lower portion of the sleeve 66, an anti-friction bearing 67 is disposed and the lower end of the spindle 63 passes therethrough and projects below the lower end of the sleeve 66. The lower portion of the spindle 63 is provided with an exterior shoulder 68 which will be drawn up against the bearing 67 by tightening the nuts 64 against bearing 65. The upper end of the spindle 63 is splined to the spindle 53 by a spline 69, which permits movement of the upper end of the spindle 63 in and out of the socket 62. This relative movement of spindle members 63 and 53 is necessary when the sleeve 66 is moved into and out of the sleeve 50. The lower end of the sleeve 50 is split and a clamp 70 is associated therewith to clamp the lower end of sleeve 50 around the sleeve 66 or to release sleeve 66 to permit vertical movement thereof.

For moving the sleeve 66 in and out of the sleeve 50, a cam device 71 is provided. This cam device includes a cam 72 rotatably carried on a bushing 73 which is supported by a pin 74 extending radially from the sleeve 50. The pin 74 is threaded into a socket 75 intermediate the upper and lower ends of sleeve 50. The cam 72 is provided with an arcuate slot 76 (Figure 7) which receives the bushing 77 carried by a pin 78. This

pin 78 is threaded into the sleeve 66, as indicated at 79. The pin 78 projects radially outwardly from sleeve 66 through a vertical slot 80, formed in the sleeve 50 below the socket 75. The cam 72 is rotated around the axis of pin 74 by means of a knob 81 keyed thereto, as at 82. The knob 81 is also rotatably mounted on the bushing 73, being retained in place thereon by the cap 83 of the pin 74 which engages a washer 84 that bears against an interior shoulder on the cap as shown. The cap 71 is provided with diametrically opposed openings 85 in its hollow outer end 86 through which a pin 87 is passed transversely. The pin 87 is provided with a removable knob end 88 to permit insertion of the pin in the openings 85 when removed. Surrounding the cap 83 of pin 74, is a compression spring 89 which bears against the washer 84 and the pin 87. The pin 87 may be slipped back and forth through the cap 81 and will be retained in position by the spring 89.

It will be apparent that if clamp 70 is released, the sleeve 66 may be adjusted in and out of sleeve 50 by rotating cam 72 through the medium of the lever pin 87. The amount of leverage desired for rotating the cam can be varied by sliding the pin 87 transversely of cap 81. Rotating cam 72 will move the pin 78 vertically in slot 80 and consequently, will move the sleeve 66 vertically relative to sleeve 50. The clamp 70 may again be tightened to hold sleeve 66 in any fixed position relative to sleeve 50.

The spindles 53 and 63 and associated bearings may be lubricated by means of a lubricant-conducting bore 53a extending from the upper end of spindle 53 into the socket 62. Above the spindle 63 in socket 62, packing 90 may be provided. Below the lowermost bearing 67, a cap 91 is threaded into the sleeve 66 and will retain sealing rings 92 in position therein.

The lower end of spindle 63 is hollow and is provided with a socket 93 for receiving a split collet 94. This collet is provided with a tapered lower end 95 for cooperating with a similar taper on the socket 93 and is moved in and out of the socket by means of a collar 96 threaded on the exterior of spindle 63 at the lower end thereof. The collet 95 is designed to receive in its socket 97 any standard type of cutting, boring, or similar tool.

The sleeve 31, carried by column 26, also supports the pantograph 100. It will be noted from Figure 1, that the sleeve is provided with a depending bracket 101 bolted to the lower end thereof. This bracket is pivoted by a pin 102 to the rear end of a supporting arm 103. The forward end of the arm 103 is connected to the rear arm 104 of the pantograph frame 100 by means of a clamping and guide member 105. The arm 104 slidably passes through the clamp 105 which may be releasably clamped thereto by means of an operating screw 106. The member 105 is pivotally carried by a second clamping and guide member 107 which is mounted below the arm 103 but which has a guide portion 108 disposed in a slot 109 which is formed along the length of the arm 103. The second clamp member 107 may be actuated by means of a screw 107a. Thus, the clamp member 105 may be set at any position along the supporting arm 103 and the arm 104 of the pantograph can be moved to any desired position in the clamp 105 which may then be actuated to clamp it in such position. The pantograph frame is further provided with the front arm 110, the end arm 111, and the end arm 112, which serve to form a parallelogram in the

usual way. It will be noted that all of the arms are pivotally connected together preferably by anti-friction bearings, and that the arm 112 is provided with angular ends 113 and 114, which are connected to the rear arm 104 and the forward arm 110, respectively.

The arm 112 is connected to the sleeve 50 of the forming tool unit. As a part of this connection, the lower end of the sleeve 50, as shown in Figure 6, has an anti-friction bearing 115 mounted thereon which, as shown in Figure 1, is provided with an outwardly projecting lug 116. Bolted to this lug 116, by bolts 117, is a clamping and guide member 118, which is practically identical with the clamp member 105, and which is actuated by a screw 119. When the clamp 118 is released, the forming tool unit may be swung about the pivot 47 to move the clamp 118 to any position along the arm 112 where the clamp may again be actuated to grip such arm. Thus, the point of connection of the pantograph frame 100 to the forming tool unit can be varied. This variation along with the variation of the connection of arm 103 to arm 104 and arm 104 to clamp 105, at the same time, will vary the ratio of reproduction, as will be apparent hereinafter.

A tracer supporting arm 120, as shown in Figure 1, is provided for connection to the pantograph frame 100. The outer end of this arm 120 supports the depending tracer pin 121 which is attached to the arm, as shown best in Figure 8, so that it can be adjusted vertically relative thereto. The tracer pin 121 is supported on the arm 120 by means of a sleeve member 122 threaded into an opening 123 in the arm 120 the sleeve having a nut portion 124 which clamps against the arm. The upper portion of the sleeve 122 is provided with a socket for receiving a split collet 125 which is actuated by a nut 126 threaded into the upper end of the sleeve and which moves the lower tapered end 127 of the collet into contact with a tapered surface at the bottom of the socket. Thus, by actuating nut 126, the pin 121 which slidably extends through the nut 126, the collet 125, and the sleeve 122 can be released or gripped to adjust its vertical position on the arm 120. The lower end of the pin 121 is provided with a socket 129 for receiving a pin 130 that has a template-engaging portion 131 on its lower end. The pin 130 is held in the socket 129 by means of a screw set 132. Thus, member 130 can be removed and be replaced with a similar member of different size.

When the tracer supporting arm 120 is connected to the forward pantograph arm 110, the connection shown in Figure 9 is employed. At this time, the overlapping portions of the arms 110 and 120 are in contact and a pair of clamping bolts 133 are passed through aligning openings formed therein and spacers 134 are associated with the opposite side of the arm 110. However, when the arm 120 is attached to the pantograph arm 111 at the rear of the pantograph as shown by dotted lines in Figure 2, the connection is made as in Figure 10. In this case, the bolts 133 are passed through a pair of aligning openings in the arms 120 and 111 the spacers 134 being disposed between the overlapping portions of the arms so that the arm 120 clears the rear arm 104 of the pantograph frame. Thus, the tracer supporting arm may be mounted at either of two diagonally opposed positions to correspond to the selected position of the master supporting table 10. To aid bar 11 in supporting table 10, the table top 2 may carry an ad-

justable upstanding screw 135 for engaging the lower surface of table 2 at a point spaced to one side of bar 11. With this arrangement, the table 10 can be supported parallel to table top 2. As will be apparent later, when the table 10 is at the forward corner, the reproduction will be a direct image of the master in lesser degree, while when it is at the rear corner, the reproduction will be an image of the master which has been swung around 180° relative to the master in a plane parallel to the plane of the master.

It will be noted from Figure 1, that the master table 10 is provided with a plurality of the openings 19 any of which not in use with clamp 17, may receive the tracer pin 121, when it is desired to lock the pantograph frame to the table and to prevent movement thereof, for example, when the machine is not in use.

In Figure 6, I have illustrated a drilling tool T in the collet 94. However, it is to be understood that this collet may receive and retain any suitable forming tool, such as a cutting tool, a grinding tool, an air hammer, or any other suitable tool.

In using this machine, the workpiece W is first fastened to the table top 2 at the center thereof. This may be accomplished with a vice or with clamping screws or if the workpiece is thin, it may even be pasted to the table top. In locating the workpiece, the straight edge 4 may be used and will serve as a guide for locating several identical workpieces on the table, successively. The ratio of reproduction is determined or selected and the connection of the pantograph 100 to the supporting arm 103 and the connection of such pantograph to the forming tool unit sleeve 50 are adjusted to properly position the tool and tracer relatively to obtain this ratio. If the master table 10 is positioned, as indicated in full lines in Figure 2, the image reproduced on the workpiece will be a direct image smaller than the master. On the other hand, if the master table 10 is positioned, as indicated in dotted lines in Figure 2, the image reproduced on the workpiece will be swung around 180° relative to the master in a plane parallel to that of the master. This latter image may be smaller or larger than the master depending upon the position of the arm 104 of the pantograph in the clamp 105. The template or master M is formed or selected and is positioned on the table 10, being suitably secured thereto, as previously indicated, the straight edge 22 aiding in locating the template. In setting the ratio on the pantograph 100, the forming tool is roughly set over the center of the workpiece. The master table 10 is adjusted forwardly and rearwardly on the bar 11 and laterally on the table top until the master M is suitably located under the tracer pin 121 where it is clamped. By operating handle 39, when clamp 32 is released, the supporting sleeve 31 is moved vertically on the column 36 to move the forming tool unit and pantograph vertically. The sleeve 50 is raised in this manner to such an extent that by releasing clamp 70 thereof and operating the cam lever 87, the sleeve 66 can be lowered until the pin 78 contacts the lower end of slot 80.

The handle 39 is now again operated in order to lower the forming unit until the forming tool T touches the workpiece, which is the point where the cutting or other forming operation starts. The cam lever 87 is now actuated to move the sleeve 66 to its uppermost position and raise the

cutter from the work. The handle 39 is set on zero position and is then rotated to lower the forming tool unit to the depth indicated on dial 40, which will be the selected depth of cut into the workpiece. The clamp 32 is now actuated to clamp the sleeve 31 in fixed position and, therefore, hold the sleeve 50 on the forming tool unit in a fixed vertical position. At this time, the tracer pin 121 is adjusted down until it contacts firmly with the master-supporting plate 23. If the machine is now started and the tracer pin is held against the template and moved therearound and if the sleeve 66, which supports the cutting tool is gradually lowered by means of the cam lever 87, the cutter will cut into the workpiece to the proper depth, which is determined by the pin 78 contacting the lower end of the slot 80. Thus, the master M will be produced in the workpiece W in the proper ratio. With the same setting of the machine, any desired number of articles can be reproduced from the same master.

When the machine is to be used on a large heavy object which cannot be supported on the main table, such object can be disposed directly behind the main table. The tracer arm 120 will be in the position on the pantograph frame 100 shown by the dotted lines in Figure 2. However, the column 26 will be turned in socket base 27 until the pantograph frame and associated parts 30 are completely behind the main table, the arm 120 then extending forwardly over the right-hand side of the main table. So as to cooperate with the tracer point 121 on arm 120, the master table 10 will be disposed on the right-hand side of the main table and will be disposed on track bar 11 adjacent the rear end thereof so as to be at the rear side of the main table.

It will be apparent from the above description, that I have provided a pantographic reproduction machine having many desirable characteristics. A number of advantages of my machine have been discussed above and others will be apparent.

Having thus described my invention, what I claim is:

1. A pantographic reproduction machine comprising a support, a master supporting unit, a workpiece supporting unit, means for attaching said master supporting unit and means for attaching said workpiece supporting unit to said support, a pantograph frame attached to said support for movement in a plane parallel to the master and workpiece supporting units, a forming tool unit connected to said support for movement in a plane parallel to the plane of said support and connected to said pantograph frame so that its movement is controlled thereby, a tracer carried by said pantograph frame for cooperation with said master, said means for attaching said master supporting unit to said support permitting attachment thereof to the support at either of two diagonally opposed locations at opposite sides of the workpiece supporting unit, and means for attaching said tracer at either of two diagonally opposed points to said pantograph frame for cooperation with said master in its selected position.

2. A machine according to claim 1 wherein the means for attaching said master supporting unit to said support comprises connections between said master supporting unit and said support which permits adjustment of said master supporting unit relative to the support in all directions in a plane parallel to said pantograph frame at either of the positions of said unit.

3. A machine according to claim 2 wherein the connections between the pantograph frame and the support and between such frame and the tool unit are adjustable to vary the ratio of reproduction.

4. A machine according to claim 3 wherein the forming tool unit and the pantograph frame are connected to said support for simultaneous adjustment in a plane perpendicular to said support.

5. A machine according to claim 4 wherein the tracer is adjustable in a plane perpendicular to the pantograph frame.

6. A machine according to claim 5 wherein the forming tool unit includes a tool holder adjustable at right angles to the plane of movement of said unit.

7. A machine according to claim 6 wherein means is associated with said tool unit for feeding the tool at right angles to its plane of movement and means is provided for limiting the extent of such movement.

8. A pantograph reproduction machine comprising a horizontally disposed supporting table, a master supporting unit, a workpiece supporting unit, means for attaching said workpiece supporting unit to said table, means for attaching said master supporting unit to said table at either of two positions on opposite sides of the workpiece, said last-named means permitting universal adjustment of the master supporting unit relative to the table, a supporting column attached to said table, a pantograph frame attached to said column for swinging movement in a horizontal plane parallel to said table, a forming tool unit supported by said column for movement in a horizontal plane parallel to said table, and connected to said pantograph frame so that its movement is controlled thereby, a tracer pin carried by said pantograph frame and depending therefrom for cooperation with said master, and means for attaching said tracer pin to said pantograph frame at either of two diagonally opposed points on said frame for cooperation with said master in its selected position on the table.

9. A pantographic reproduction machine according to claim 8 wherein the master supporting unit comprises a plate mounted on a guide rail for adjustment therealong, said guide rail being supported on the table for adjustment laterally of said column.

10. A pantograph reproduction machine according to claim 9 wherein means is provided for clamping said plate to said guide rail at a selected position, said guide rail being supported by guides cooperating with the opposed edges of said table, and means associated with said guide rail and connected to said guides for clamping them to the edges of said table.

11. A machine according to claim 10 wherein a supporting member is provided on said column for supporting said pantograph frame and said forming tool unit, said pantograph being carried by an arm pivoted to said member for horizontal movement and said forming tool unit being carried by a parallel arm pivoted to said member for horizontal movement, and means for vertically adjusting said member on said column.

12. A machine according to claim 11 wherein said supporting member is a split sleeve and

clamping means is associated therewith for clamping it to the column.

13. A machine according to claim 12 wherein the means for adjusting the sleeve on the column comprises a screw anchored on the column and engaging a threaded member carried by the sleeve.

14. A machine according to claim 13 wherein the pantograph frame is connected to its supporting arm by a clamp member adjustable along the associated arm of the pantograph frame and adjustable along the pantograph frame supporting arm, and wherein the tool unit is connected to another arm of the pantograph frame by a clamp member adjustable along said arm.

15. A machine according to claim 14 wherein the forming tool unit is supported on its supporting arm for vertical movement relative thereto, a tool carried by said forming tool unit, means carried by said arm for actuating the tool, means for feeding the tool downwardly, and means for limiting the extent of its downward movement.

16. A machine according to claim 15 wherein the actuating means comprises an electric motor which drives the forming tool which tool is rotatably supported by said forming tool unit, said forming tool unit and said electric motor being disposed at opposite sides of the arm of the supporting unit so as to counterbalance each other.

17. A machine according to claim 16 wherein the forming tool unit comprises a vertically disposed sleeve, a second sleeve slidably disposed within the first sleeve, means carried by the second sleeve for supporting the tool, means for moving the second sleeve downwardly relative to the first sleeve to feed the tool into the work, and means for limiting the downward movement of the second sleeve.

18. A machine according to claim 17 wherein the means for moving the second sleeve downwardly comprises a cam connection between the first and second sleeves, said cam connection including a pin carried by one of the sleeves and extending into a vertical slot in the other sleeve to limit relative vertical movement thereof.

19. A machine according to claim 18 wherein the first sleeve is split and has the second sleeve disposed therein and is provided with a clamp adjustable to clamp it around the second sleeve.

20. A machine according to claim 8 wherein the master supporting unit comprises a plate having a straight edge adjustably mounted thereon and wherein the supporting table is provided with a straight edge adjustably mounted thereon for cooperation with the workpiece.

GEO. M. KECZELI.
